United States Patent

Des. 236,836
Patented Sept. 16, 1975

236,836

SPEAKER CABINET

John R. Cerra, Omaha, Nebr.
(1405 Early St., Sac City, Iowa 50583)

Filed July 30, 1973, Ser. No. 383,571

Term of patent 7 years

Int. Cl. D14—01

U.S. Cl. D26—14 G

FIG. 3

FIG. 4

FIG. 1

FIG. 2

FIG. 1 is a rear elevation of the speaker cabinet of this invention.

FIG. 2 is a front elevation with criss-crossed lines to indicate fabric not drawn completely across the forward surface for convenience of illustration.

FIG. 3 is a top plan view.

FIG. 4 is a view as the invention would be seen from the right or left sides.

I claim:

The ornamental design for a speaker cabinet, as shown.
